Primary Examiner—Louis Zarfas*Assistant Examiner*—David Muller(74) *Attorney, Agent, or Firm*—Brinks Hofer Gilson & Lione(57) **CLAIM**

We claim the ornamental design for a puncture needle cartridge, as shown and described.

DESCRIPTION

FIG. 1 is a top perspective view of a puncture needle cartridge of the present invention;
FIG. 2 is a first side view thereof;
FIG. 3 is a second side view thereof;
FIG. 4 is a third side view thereof;
FIG. 5 is a fourth side view thereof;
FIG. 6 is a top view thereof; and,
FIG. 7 is a bottom view thereof.
